UNITED STATES PATENT OFFICE.

EARL A. TEETS AND HARVEY V. VARNER, OF CLARKSBURG, WEST VIRGINIA

ANTISEPTIC INSTRUMENT-CASE.

1,016,529.

Specification of Letters Patent.

Patented Feb. 6, 1912.

Application filed September 26, 1910. Serial No. 583,789.

To all whom it may concern:

Be it known that we, EARL A. TEETS and HARVEY V. VARNER, residents of Clarksburg, in the county of Harrison and State 5 of West Virginia, have invented a new and useful Improvement in Antiseptic Instrument-Cases, of which the following is a specification.

This invention relates to a case for clinical 10 thermometers and other instruments, and the purpose is to provide a case in which such instruments can be conveniently and safely stored and carried in the pocket and which will render and maintain the same anti- 15 septic.

The invention comprises the construction and arrangement of parts hereinafter described and claimed.

In the accompanying drawing Figure 1 is 20 a vertical section through the preferred form of the device; and Fig. 2 is a vertical section through a modified form of the device.

In the form shown in Fig. 1 the thermometer or other instrument 1 is contained in a tube 2 formed of glass or other suitable vitreous material closed at its bottom 3 and open at the top. This glass or similar tube is contained within an outer casing 4 of 30 metal or other suitable material to act as a protection. The closure at the top is effected by means of a cap or cover 5, having a threaded connection at 6 with the upper end of the metal tube 4, and being provided on 35 its inner face with a suitable cushion or packing washer 7 adapted when the cover is screwed down to bear against the upper end of the glass tube, said glass tube projecting slightly above the upper end of the metal 40 tube for this purpose. For convenience in screwing on and unscrewing the cover the latter is provided with a knurled rim 8 preferably below its upper end, so as to have a portion projecting above said knurled rim 45 to assist in properly holding and guiding the cover when screwing it onto or off the tube. In the bottom of the tube is a light helical spring 10 adapted to form a yielding or cushion support for the lower end of the instrument and also to lift said instrument when the cover is taken off so as to project its upper end above the upper end of the tube in order that the same may be readily grasped to withdraw the instrument from 55 the tube. A seat for the thermometers or other instruments is formed by means of a

table 11, which preferably is cupped and made of considerable depth, as shown, so as to guide the table 11 and prevent the same from binding in the tube. This cup preferably is perforated, as shown, in order to permit the antiseptic liquid, such as alcohol, to freely pass therethrough. Preferably one side of the metal tube 4 is cut away near the upper end to provide the window 13 through which the instruments can be viewed, and through which it can be ascertained without opening the tube whether there is any antiseptic liquid therein. A small hole 14 is in the bottom of the outer tube to permit any alcohol which gets between the inner and outer tubes to leak out. A rubber or other cushion 15 is also preferably placed between the bottoms of the inner and outer tubes.

The modification shown in Fig. 2 is of 75 simpler construction, the interior glass tube being omitted and the outer metal tube being continuous or unprovided with the window 13. In other particulars it is the same as the main modification.

In using the device the tube is partly filled with an antiseptic liquid such as alcohol, and the thermometers or other instruments are inserted into the same, resting upon the table 11. The cover 5 is then screwed onto 85 the upper end of the tube until its cushion or gasket 7 is pressed firmly against the upper end of the tube, thereby making a practically hermetical seal at the upper end. The act of screwing the cover down de- 90 presses the instrument, lowers the table 11 and compresses spring 10, so that when closed the instruments are held between the cushion or gasket 7 in the cover and the yielding seat or table 11. When the cover is 95 unscrewed spring 10 expands, thereby lifting the instrument so that its upper end projects above the tube and can be readily grasped for removal.

Obviously the case may be made of any 100 size or dimension and adapted to hold one or any desired number of instruments or implements. By altering the size and shape of the case any desired implements may be provided for. In lieu of a glass tube we 105 may use a thin porcelain tube or an inner tube of other material.

What we claim is:

1. An antiseptic instrument case comprising a tube formed of impervious material 110 which can be antiseptically treated, said tube being permanently closed at its

lower end and of greater depth than the instrument to be received, a support for the instrument in the bottom of the tube, a coiled spring pressing upwardly on said support and of such length as to lift the instrument to project above the upper end of the tube, and a cover engaging the upper end of the tube, sealing the same, and being independent of the instrument and arranged to engage the upper end thereof and depress the same to compress the spring.

2. An antiseptic instrument case comprising a tube formed of impervious material which can be antiseptically treated, said tube being permanently closed at its lower end and of greater depth than the instrument to be received, a perforated cup-shaped support for the instrument in the bottom of the tube, a coiled spring pressing upwardly on said support and of such length as to lift the instrument to project above the upper end of the tube, and a cover threaded onto the upper end of the tube, sealing the same, and being independent of the instrument and arranged to engage the upper end thereof and depress the same to compress the spring.

3. An antiseptic instrument case, comprising a non-frangible outer tube and a vitreous inner tube, both open at their upper ends and closed at their inner ends and of greater depth than the instrument to be received, a support for the instrument in the bottom of the inner tube, a coiled spring pressing upwardly on said support and of such length as to lift the instrument to pro-

ject above the upper ends of said tubes, and a cover engaging the upper end of the outer tube, pressing against and sealing the upper end of the inner tube, and independent of the instrument and arranged to engage the upper end thereof and depress the same to compress the spring.

4. An antiseptic instrument case comprising a glass tube permanently closed at its lower end and open at its upper end and of greater depth than the instrument to be received, a non-frangible outer protecting casing inclosing said glass tube, and provided with a side opening therethrough, said inner tube projecting slightly above the upper end of said outer tube, a support for the instrument in the bottom of the inner tube, a coiled spring pressing upwardly on said support and of such length as to lift the instrument to project above the upper ends of said tubes, and a cover engaging the upper end of the outer tube, pressing against and sealing the upper end of the inner tube and independent of the instrument and arranged to engage the upper end thereof and depress the same to compress the spring.

In testimony whereof, we have hereunto set our hands.

EARL A. TEETS.
